UNITED STATES PATENT OFFICE.

JONAH W. MOYER, OF PHILADELPHIA, PENNSYLVANIA.

ABATTOIR.

SPECIFICATION forming part of Letters Patent No. 447,840, dated March 10, 1891.

Application filed November 4, 1890. Serial No. 370,273. (No model.)

To all whom it may concern:

Be it known that I, JONAH W. MOYER, of the city and county of Philadelphia, and State of Pennsylvania, have invented an Improvement in Abattoirs, of which the following is a specification.

My invention has reference to abattoirs; and it consists of certain improvements, all of which are fully set forth in the following specification, and shown in the accompanying drawings, which form a part thereof.

The object of my invention is to provide a construction of tracks for an abattoir, which shall facilitate the proper handling of hogs or other animals, with particular reference to that portion of the slaughter-house where the hog is halved and delivered to the chill-room.

The various features of my invention will be easily understood by reference to the accompanying drawings, in which—

Figure 1 is a plan view of a portion of an abattoir, showing my improvements applied thereto. Fig. 2 is a sectional elevation of a portion of the same, taken on line $y-y$ of Fig. 3; and Fig. 3 is a longitudinal sectional elevation of same, taken on line $x-x$ of Fig. 2.

A is the scalding tank or vat.

B is a scraping-table or apparatus for removing the hair from the hog.

C is a track upon which the hog is hung by means of a small trolley, such as shown at P in Fig. 3. After the hog is scraped a gambrel-stick O is placed through the joints of the rear legs, as shown in Fig. 2, and this 35 gambrel-stick is hung upon a hooked portion P of a trolley P. The hog is then run around upon the railway C, which is suspended from the ceiling, and the weight of the hog is taken on the scales D. After being weighed the 40 whole hog is moved farther along the track C onto a track E, from which it may be shifted onto any one of a series of short tracks F by means of switches e.

Arranged between the several tracks F and at a lower level are a series of short wooden runs G, which are preferably made of wood and are provided with lateral grooved guide portions g, into which the enlarged heads of the gambrel-stick O are received, as shown in Fig. 2. These runs G have their curved guides g inclined downward at each end, as indicated by the letter R in Fig. 3. The runs are sus-

pended from the ceiling by rods N or otherwise, and may be formed of wood or metal, but preferably of wood.

55

Arranged above the rear ends of the several runs G is a series of tracks H, which lead to a transverse track I, with which they may be connected by switches i, and this track I connects by a short section of track J, passing through 60 a doorway into the chill-room K, with a series of parallel tracks L by means of switches I. The hog is conveyed to the runs, and while supported by said runs it is halved, and the two halves are secured upon independent trolleys P and are run over the adjacent tracks H on the track I, and thence into the chill-room to the tracks L. The gambrel-sticks O are loosely supported in hooked portions p of the trolleys P, so that they are disconnectible 65 therefrom. When the trolley is moved to the end of the track F, the gambrel-stick will be over the grooves g of the runs G, as shown in Fig. 2, and when the trolley drops into the notch h of the track F the gambrel-stick is 70 brought to rest upon the runs G, and the hook p of the trolley falls from its connection with the gambrel-stick, as indicated in Fig. 3. While the gambrel-stick, with the hog attached thereto, is hanging upon the runs G, a 75 friction sufficient is produced to prevent swinging of the hog during the halving thereof. As soon as the hog is halved, and while still supported by the gambrel-stick, hooks Q of another set of trolleys P on the tracks H 80 are hooked into the joints of the hind legs, as shown in Fig. 3. The halves of the hog, with the gambrel-stick, are then pushed in the direction of the arrow, Fig. 3, until the gambrel-stick leaves the runs G. The halves of 85 the hog will then be upon the two trolleys and upon separate tracks. The gambrel-stick may now be removed and each of the halves of the hog run over the tracks independently.

95

The run G is made extremely short, as its only function is to hold the hog during the halving thereof and during its transfer from the single track F to the double tracks H H.

By the use of this apparatus it is evident 100 that at no time is it required to lift the weight of the hog from the time it is placed upon the track C to the time it is received in the chill-room K, for during the release of one trolley

and the attachment of the other two trolleys the weight of the hog is sustained by the gambrel-stick and the runs G.

I do not limit myself to the minor details of construction herein set out, as they may be modified in various ways without departing from the spirit of my invention.

Having now described my invention, what I claim as new, and desire to secure by Letters

10 Patent, is—

1. The combination of a track, two runs arranged upon either side of said track, two tracks arranged substantially in line with the two runs, separate trolleys for each of the tracks, and a gambrel-stick adapted to be supported by the trolley of the first-mentioned track, whereby a hog may be supported upon the gambrel-stick and conveyed to the runs and after being halved the halves be sustained by the separate trolleys on the remaining tracks and conveyed to a distant place.

2. The combination of a track, two runs arranged upon either side of said track and having grooved guides which are inclined downward at each end, two tracks arranged substantially in line with the two runs, separate trolleys for each of the tracks, and a gambrel-stick adapted to be supported by the trolley of the first-mentioned track, whereby a hog may be supported upon the gambrel-stick and conveyed to the runs and after being halved the halves be sustained by the separate trolleys on the remaining tracks and conveyed to a distant place.

3. The combination of a track having a notch in its upper portion, two runs arranged upon either side of said track and arranged below the notch of said track, two tracks arranged substantially in line with the two runs, separate trolleys for each of the tracks, and a gambrel-stick adapted to be supported by the trolley of the first-mentioned track, whereby a hog may be supported upon the gambrel-stick and conveyed to the runs and after being halved the halves be sustained by the separate trolleys on the remaining tracks and conveyed to a distant place.

4. The combination of a track E, a series

50 of short tracks F, arranged at an angle there-

to, a series of switches e, forming a connection between either of said tracks F and the track E, a series of runs G, arranged between the tracks F, a series of tracks H, arranged substantially in line with the runs G, and separate trolleys for the tracks H, whereby a trolley with a whole hog may be conveyed over the tracks E and F to the runs G, upon which the said hog is sustained during halving and from which the halves may be removed by separate trolleys upon the tracks H H.

5. The combination of a track E, a series of short tracks F, arranged at an angle there-to, a series of switches e, forming a connection between either of said tracks F and the track E, a series of runs G, arranged between the tracks F, a series of tracks H, arranged substantially in line with the runs G, a track I, communicating with all of the tracks H by 60 means of switches i, a chill-room provided with tracks, a track connecting the tracks of said chill-room with the track I, and separate trolleys for the tracks H, whereby the trolley with a whole hog may be conveyed over the 65 tracks E and F to the runs G, upon which the said hog is sustained during halving and from which the halves may be removed by separate trolleys upon the tracks H H and conveyed over the tracks H and I into the 70 chill-room.

6. The combination of a railway leading from the slaughtering and scalding portion of the abattoir, two short runs arranged at a point of said railway distant from said 85 slaughtering and scalding portion of the abattoir, a gambrel-stick adapted to support the hog and rest upon the runs during halving, a trolley adapted to the railway and supporting the gambrel-stick, and a railway extend- 90 ing beyond the runs, whereby the halved hog may be conveyed to a distant place with but little friction.

In testimony of which invention I have hereunto set my hand.

J. W. MOYER.
